HEAT TREATING APPARATUS

Odin V. Carlson, New York, and Arthur K. Seemann, Garden City, N. Y., assignors to The Linde Air Products Company, a corporation of Ohio

Application August 18, 1938, Serial No 225,520

18 Claims. (Cl. 266—4)

This invention relates to heat treating apparatus, and more particularly to apparatus for heat treating surface portions of metal bodies, such as the ends of tread surfaces of rails or the like.

During service in track, the ends of rail tread surfaces are subject to a greater amount of wear than the remainder of the tread surfaces due to the impact of rolling stock in passing over a joint from the end of one rail onto the end of an adjacent rail. The amount of such wear may be reduced, and the life of the rails increased, by hardening the tread surfaces at the ends of the rails. An effective method of hardening consists in locally heating only the portion to be hardened to a temperature at or above the critical range, and then cooling the heated portion. Local heating may be accomplished electrically, either by induction or by passing an electric arc over the surface portion to be hardened, or by directing against the surface portion to be hardened high temperature heating flames, usually formed by a combustible mixture of gases, such as oxygen and acetylene. This latter process is known as "flame hardening," and this invention will be explained with reference thereto, although it will be understood that other ways of heating the tread surfaces may be employed. Furthermore, the usual rail steel normally requires only the application of an air quench in order to produce the desired hardness, but some rail steels will harden upon natural cooling. This invention will be explained with reference to air quenching, but it will be understood that natural cooling or other methods of cooling may be employed where the nature of the metal or other considerations indicate that such is desirable.

Previously, rail ends have been surface hardened after being laid in track, but such a procedure necessitates the use of a wheeled carriage adapted to roll along the track, and also a considerable amount of apparatus mounted thereon. Much time is consumed in rolling the carriage up and down the track, in adjusting the apparatus for each particular joint, and in removing the apparatus from the track upon the approach and passage of a train or other equipment normally using the track. One object of this invention is to provide apparatus adapted to heat treat the ends of rails prior to their installation in track, and more particularly at a place at which a considerable number of rails are stored, such as on storage beds or docks at steel mills.

During their normal progress through a mill, after being rolled and hot-sawed into lengths, 55

rails are placed on cooling beds. After cooling, the rails are taken to straightening presses; the required holes are drilled in the webs at the scales; and the rails are then taken to docks, usually located outside, for final inspection. It is while the rails are stored at the scales or on the docks that the most advantageous time occurs for surface hardening the ends, since the ends are easily accessible, a plurality of similar rails are disposed in an orderly arrangement, and there is the least likelihood of interfering with any other operation. Apparatus previously used for surface hardening rail ends has not been adapted for use at such places, and the advantages of heat treating a plurality of similar rails at such places has never been fully realized.

The main objects of this invention are to provide apparatus for rapidly, effectively and uniformly heat treating surfaces of metal bodies and more particularly the ends of rails; to provide such apparatus which is portable and may be removed easily from one rail end and held in position for similarly treating another rail end; to provide such apparatus which is sufficiently adjustable to produce the optimum results; to provide such apparatus which is adapted to be utilized in heat treating a plurality of similar rails with a minimum of time and effort; to provide such apparatus which need be adjusted only for the first of a plurality of similar rails; to provide such apparatus in which the parts thereof are protected from overheating; to provide such apparatus which may be used outside even in the most severe weather; to provide such apparatus which will be simple and economical in operation; and to provide such apparatus which is semi-automatic or substantially completely automatic in operation.

Other objects and novel features of this invention will become apparent from the following description and accompanying drawings, in which:

Fig. 16 is a transverse vertical sectional view taken along the line 16—16 of Fig. 15; and

Fig. 17 is a side elevation of the apparatus of Fig. 1 and auxiliary equipment used in a complete set-up for surface hardening rail ends.

Apparatus constructed in accordance with this invention, as illustrated in Fig. 1, includes a carrier or framework F which is preferably made of tubular members both for the sake of strength and lightness and also so that a cooling medium may be circulated therethrough, but hollow castings or other parts having cooling passages may be used instead. The tubular members are preferably assembled by welding, and other fixed component parts of the apparatus attached or secured thereto by welding, but it will be understood that other ways of attaching or securing the various parts together may be utilized.

The carrier or framework F carries a heating head in which is adapted to direct a plurality of high temperature heating flames from tips T upon the end of the tread surface of a rail R. The framework F also carries a retractable quenching head Q which is adapted to direct a plurality of jets of air onto the heated surface, and a protective air-screen head S which is adapted to direct a blast of air rearwardly along the web of the rail and also forwardly toward the quenching head when in its retracted position Q'. The framework is adjustable laterally and longitudinally with respect to the end of the rail; and the framework is also pivotal vertically with respect to the end of the rail, principally so that the lower face of the heating head H and tips T may be positioned substantially parallel to the tread surface of the rail and in approximate operating position. For further vertical positioning, the heating head H and quenching head Q are adjustable vertically with respect to the framework.

A cooling medium is passed from an inlet I at the front lower end of the framework to the rear upper end thereof, and thence through a connecting hose K to the heating head H. From the heating head, the cooling medium is passed through a jacket J of a 180° adaptor A by means of a connecting tube M, and led from the jacket through a tube N to an outlet O.

The adaptor A connects two blowpipes B with the heating head H to supply the heating head with a combustible mixture of gases, such as oxygen and acetylene. A pilot tip P is adapted to direct a small flame, formed from an air-fuel

gas mixture, toward the heating head H in order to ignite the heating flames when the combustible mixture issues from the tips T. Valves for controlling the flow of gases to the blowpipes B, as well as for controlling the flow of air to the air-screen and quenching head, are installed in a cabinet C mounted on the framework; and the heating head H, adaptor A, blowpipes B, and cabinet C are vertically adjustable as a unit on the carrier or framework.

The control valves for the heating gases and air are interlocked and operated simultaneously by a lever L, which is also the handle of the gas control valve. The lever L is adapted to move the quenching head Q from quenching to retracted position Q', and vice versa, and also to operate the air control valve, which is so constructed that, when air is flowing to the quenching head Q, the supply to the protective screen head S will be shut off, and vice versa. In addition, a latch is associated with the lever L, which holds the lever in the "on" position against the tension of a suitable spring, and an automatic timing mechanism is associated through an electrical cable E with a solenoid connected with the latch, the solenoid being adapted to trip the latch and thereby permit the lever L to be pulled to the "off" position by the spring.

In general, when the lever L is thrown to the "on" position, the flow of combustible mixture to the head H is turned on, the quenching head Q is simultaneously moved to its retracted position Q', and the flow of air to the protective screen head S is also turned on. After a predetermined interval of heating, the flow of mixture to the head H is automatically shut off, the head Q is moved forwardly into quenching position, and the flow of air is simultaneously directed through the quenching head. A more specific description of the parts involved in these operations will be given later.

The framework F, as in Figs. 1-3, includes two main vertical tubes or posts 20 to which the cabinet C is secured by clamps 21. From the upper ends of posts 20, a pair of truss structures, consisting of horizontal tubes 22 and 23, extend forwardly along each side of the web W of the rail. The tubes 22 and 23 converge inwardly toward the rail and also toward each other at their rear ends, there being connected together and to a rectangular tubular member or cross-over 24 extending upwardly and over the head or ball U of the rail.

For preliminary positioning of the heating head H with respect to the rail, pivoting skids 25 and adjustable angles 26 are utilized. The skids 25, which are welded to the lower horizontal tubes 23 adjacent the end of the rail, contact the upper surface of the base V of the rail. The angles 26, which engage the underside and side of the head U, are pivoted upon bolts 27 and are adjustable through clamps 28 both radially and vertically upon the vertical legs of crossover 24. The angles 26 are raised or lowered to cause the apparatus to pivot on skids 25 in positioning the lower face of the heating head H substantially parallel to the tread surface of the rail; while the weight of cabinet C, blowpipes B, and other parts at the front end of the framework serve by their weight to hold angles 26 in engagement with the head of the rail and hold the apparatus in fixed position longitudinally of the rail.

To provide a more rigid structure, a pair of braces 29 are welded to upper tubes 22 and to the upper corners of cross-over 24, the braces 29

passing upwardly around the head of the rail. The convergence of tubes 22 and 23, and the position of cross-over 24 and braces 29, as well as skids 25 and angles 26, permit the apparatus to be placed upon any one of a number of closely placed rails, since from Fig. 2, it may be seen that each of these parts is disposed sufficiently closely to the web and head of the rail under treatment to prevent contact with rails laid side by side and with the base of each touching the base of the rail under treatment.

For lateral positioning, a pair of eccentric rollers 30 contacting the web W on either side thereof are utilized. The eccentric rollers are mounted on studs 31 welded to the lower horizontal tubes 23, and are secured in any desired position, by suitable means, such as nuts 32.

For longitudinal positioning, a stop 33 is welded to the lower horizontal tubes 23, and an upper flange 34 of the stop is adapted to contact the end of the web W, when the apparatus is placed on the rail. Longitudinal adjustment is provided by a set screw 35 engaging a suitable threaded hole in the lower portion of stop 33 and contacting the end of the base V.

A rear handle 36, which is hollow in order to permit the flow of cooling medium therethrough, is welded to the upper side of the upper horizontal leg of cross-over 24, and permits the apparatus to be lifted at that point. Attached to the lower side of the upper leg of cross-over 24 are a pair of skids 37, normally disposed above the tread surface of the rail when the apparatus is in operating position, but adapted to contact and slide along the tread surface when the apparatus is being placed on or taken off the end of a rail. It will also be apparent that front skids 25, rear skids 37, and angles 26 cooperate to prevent injury or damage to tips T through contact with the rail while the apparatus is being placed on or taken off the end of a rail.

A tube 39, disposed laterally above the cabinet C and connected to posts 20 by horizontal tubes 40, serves as a front handle for the apparatus. A pair of U-shaped rockers 41 attached to either end of the front handle lead downwardly therefrom and then upwardly, being attached to stop 33 and the mid-portion of lower horizontal tubes 23, while braces 42, attached to rockers 41 and to posts 20 adjacent the lower ends thereof, provide a more rigid structure. The U-shaped rockers 41 protect the blowpipes B and the various connections beneath the cabinet C from injury when the apparatus is removed from a rail and set down, the apparatus preferably being rocked forward onto the junction of tubes 22 and 23 and cross-over 24.

The blowpipes B, which partially support the heating head and adaptor, are attached to the cabinet C by clamps 43, and further to support the heating head and adaptor, a post 44 is provided at its upper end with a clamp 45 fastened to the jacket J. The post 44 is supported by an inverted U-shaped tube or support 46 welded to the upper horizontal tubes 22 and held rigidly in position by braces 47 which are welded thereto and to the upper ends of posts 20. The support 46 is provided at its upper end with a collar 48 in which the lower end of post 44 is vertically adjustable through a set screw 49. In lieu of the set screw 49, the post 44 may be threaded and nuts disposed above and below collar 48 for easier adjustment when clamps 21 are loosened in obtaining the exact desired vertical distance between the tips T and the tread of the rail.

The protective air-screen head S is welded to the lower horizontal tubes 23 just forward of stop 33, and the quenching head Q is mounted upon two rods 50 secured in one arm of a yoke 51 by set screws 52, vertical adjustment of the position of the quenching head Q being obtained thereby. The yoke 51 is pivoted in the ends of brackets 53 welded to the cabinet C, and the other arm of yoke 51 is actuated through a yoke pin 54 by a rod 55, a collar 56 attached to the end of the rod being slotted to permit vertical movement of yoke pin 54. Through movement of rod 55, which is actuated through the lever L, the quenching head Q is moved from the quenching to retracted position Q', and vice versa.

A cooling medium inlet tube 57, which includes the inlet I, connects the lower ends of posts 20, the cooling medium flowing from the inlet I upwardly through each of the posts. From the top of posts 20, the cooling medium flows through horizontal tubes 22 and 23 and thence through cross-over 24 and braces 29 to rear handle 36. Since rockers 41 and braces 42 are sufficiently removed from the heating zone, and support 46 and braces 47 are cooled by air directed from the air-screen head S toward the quenching head, it is normally unnecessary to pass the cooling medium therethrough. Hollow connections are made between posts 20 and horizontal tubes 22 and 23, as well as between tubes 22 and 23 and cross-over 24 and braces 29, the remainder of the connections being solid, but other connections may be made hollow in case any other parts of the framework tend to become overheated.

From the rear handle 36, the cooling medium is carried by the flexible hose K to a fork 58 from which it is led through two tubes 59 into the head H. As previously indicated, the cooling medium is led from the head H through a tube M to the jacket J of the adaptor A, and from the jacket through a tube N to the outlet O. Since the apparatus is preferably utilized in treating rails which are stored outside on docks, the cooling medium used is preferably one which will not freeze even in the severest weather, and also will not boil or vaporize and thereby lose its cooling effectiveness. A liquid suitable for this use has been found to be an ethylene glycol solution termed "Prestone," ordinarily used as an automobile radiator antifreeze. To prevent loss, the cooling medium is also preferably circulated through a closed circuit, including a pump and a cooling coil, by means of hoses 60 and 61 connected to the inlet I and outlet O, respectively.

As best shown in Figs. 3 and 4, the parts installed within the cabinet C include a gas control valve 62 and a two-way air control valve 63. The gas control valve 62 is preferably of a type which will turn on the acetylene before the oxygen to permit the heating flames to be lighted more easily, and also turn off the oxygen before the acetylene to obviate the possibility of the presence of a highly oxidizing flame at the end of the treatment. A highly oxidizing flame tends to produce a considerable amount of scale and similar oxidation of the heated surface, which will cause a reduction in hardness, and can damage the metal surface by starting a scarfing action.

Oxygen is supplied to the gas control valve 62 from an inlet 64, and from the control valve the oxygen passes through an outlet tube 65 to a fork 66. From the fork 66, oxygen is delivered through two right angle connections 67 to oxygen inlets 68 of the blowpipes. Similarly, acetylene is de-

livered to the gas control valve from an inlet 69; from the gas control valve passes through an outlet 70 to a fork 71; and from the fork 71 is delivered through two right angle connections 72 to acetylene inlets 73 of the blowpipes. The blowpipes are provided with suitable mixers for forming a combustible mixture of oxygen and acetylene, and the proportions of the constituents thereof are controlled by valves 74, which are more clearly seen in Figs. 1 and 2. Outlets 75 of the blowpipes are connected to a fork or Y adaptor 76, and the combustible mixture formed in the two blowpipes passes from fork 76 through adaptor A to gas inlet 77 of the heating head H.

To supply acetylene to the pilot tip P, a branch line 78 leads from acetylene inlet 69 through the cabinet C to the pilot tip, as in Figs. 1 and 3, a valve 79 being installed in the branch line adjacent the lower end of the cabinet to regulate the flow of acetylene therethrough. An air injector is preferably installed in branch line 78 just above valve 79 to provide an air-acetylene mixture for the pilot tip, such a mixture producing a relatively long flame which will permit the pilot tip to be positioned at a greater distance from the heating head. The pilot tip is supported in its position adjacent the heating head by the branch line 78, and the branch line is secured to one leg of support 46 by a clamp 80.

The two-way air control valve 63 is supplied with compressed air from an inlet 81, and has two outlets 82 and 83, respectively, the flow of air thereto being controlled by a piston 84 having a reduced central portion 85. When the piston 84 is in the inward or rearward position, air is directed through outlet 82 and a hose 86 to the quenching head Q, and when the piston is in the outward or forward position, air is directed through outlet 83 and a hose 87 to the protective air-screen head S.

The handle L of the gas control valve 62 is held in the "off" position by the tension of a spring 88 attached to the lever or handle L and to a stud 90. When moved from the right hand or "off" position to the left hand or "on" position, the lever L will engage a latch 91 pivoted at the top of a post 92 and prevented from dropping out of engagement with the lever by a torsion spring 93. The latch 91 may be tripped either by a hand trip 94, or a solenoid operated plunger 95.

The lever L is operatively connected with a three-armed yoke 96 by a pin 98 which is attached to the lever L and which slides in a slot 99 in the yoke, the yoke being pivoted on a fixed pin 100. The yoke 96 operates the piston 84 of the air valve 63, an electrical toggle switch 97, and the rod 55 which passes through the rear wall of the cabinet to move the quenching head Q.

When the lever L is moved from the right hand or "off" position to the left hand or "on" position, the yoke 96 will pivot, causing the heating gases to be turned on, the quenching head Q to be moved to its retracted position Q', and the piston of the air control valve to be shifted so that the flow of air to the quenching head Q will be changed to the air-screen head S. When the latch 91 is tripped, either manually or automatically in a manner to be described later, the lever L will be moved by spring 88 to the right hand or "off" position, and yoke 96 will re-pivot, causing the heating gases to be turned off, the quenching head Q to be moved to quenching position, and the piston of the air control valve to be re-shifted so that the flow of air will then be directed through the quenching head. While in

the cycle of operations just described, the flow of air will be directed through the quenching head Q while the apparatus is being moved from one rail end to another, it will be understood that a control valve may be installed in the line leading to the air inlet 81 by means of which the air may be turned off during shifting of the apparatus.

An electrically operated mechanism for effecting automatic operation of the apparatus, as in Fig. 4, includes a solenoid 102 installed in the cabinet C and adapted to operate plunger 95, the toggle switch 97, and a time delay relay D which includes a relay 103 and a synchronous motor 104. Current is received from a line 105, one side of which is connected to solenoid 102 by a wire 106, and the other side of which is connected to a terminal 107. When the lever L is thrown from left to right in order to start the heating operation, toggle switch 97 is closed, and synchronous motor 104 is started. For this purpose, current passes through wire 106 and a wire 108 to the toggle switch, thence through a wire 109 to a terminal 110, while wires 111 and 112, leading from terminals 107 and 110, respectively, complete the circuit through the winding of synchronous motor 104. After a predetermined interval of heating has passed, a rotating contact arm 113 of the synchronous motor 104 contacts a second arm 114, thereby completing the circuit through relay 103, which includes wires 115 and 116.

Upon completion of this circuit, the winding of relay 103 will become energized and cause an arm 118 to lift, closing normally open contacts 119, which will complete the circuit through the winding of solenoid 102, this circuit including contacts 119 and wires 106, 120, and 121. When the winding of solenoid 102 becomes energized, plunger 95 will be pulled upwardly, thus actuating trip 91 and permitting spring 88 to pull the lever L to the right hand or "off" position. The synchronous motor 104 is preferably provided with suitable means (not shown) which will cause the rotating arm 113 to be returned to its initial position as soon as solenoid 102 has caused latch 91 to be tripped, thereby placing the mechanism in condition for a repetition of the cycle above described and prepared for the treatment of the next rail the end of which is to be hardened.

The initial position of rotating arm 113 of synchronous motor 104 is set in accordance with the heating time necessary for the rail to be hardened, i. e., for 112 pound rail it is generally found desirable to have a heating time of about 24 seconds, whereas for 130 pound rail, a heating time of 27 seconds has been found desirable. These heating times, of course, are also affected by the tip arrangement used, which may be changed in accordance with the weight and size of the rail, as will be explained in detail later.

In some instances, particularly at mills at which sudden cessations of the supply of electricity are prone to occur, it may be desirable to arrange the electrical circuit and associated parts so that the lever L will be tripped upon a cessation of the current as well as by operation of the automatic timing mechanism. For this purpose, the alternative control mechanism of Figs. 5 and 6 is particularly suitable. In the alternative control mechanism, latch 91' is longer than latch 91, and a shorter post 92' is disposed under the lever L to change the position of the fulcrum of the latch. Generally, when current passes

through solenoid 102, latch 91' will be pulled upwardly to hold the lever L in the "on" position, and when current no longer passes through the solenoid, the weight of plunger 95 and the latch will cause the latch to be depressed, spring 89 pulling lever L back to the "off" position.

In this modification, a time delay relay D' includes the relay 103 and synchronous motor 104, as before, but arm 118 and normally open contacts 119 are replaced by a plunger 122, carrying an insulated arm 123, and normally closed contacts 124 adapted to be opened by operation of relay 103. The hand trip lever is replaced by a push button trip switch 125, one side of which is connected to a terminal 107' of line 105' by a wire 126, and the other side of which is connected to one side of solenoid 102 by a wire 127. Switch 97 is connected in series with contacts 124 by a wire 128 attached to one side of switch 97, while the other side of switch 97 is connected by wire 108 to solenoid 102 and by a wire 129 to a terminal 110' to which synchronous motor 104 and relay 103 are also connected.

The operation of this modification is similar to the operation previously described, except that when the lever L is shifted to the "on" position, switch 97 will close the circuit through both solenoid 102 and synchronous motor 104, and, when the predetermined time interval has elapsed, rotating arm 113 will contact fixed arm 114, as before, closing the circuit through relay 103 which causes contacts 124 to open and thereby opens the circuit through solenoid 102. This will cause latch 91' to be automatically tripped and the lever L to be returned to the "off" position. Obviously, a cessation of current will also cause latch 91' to be tripped, since the solenoid 102 will no longer be energized. Other ways of accomplishing the same result will readily suggest themselves.

The heating head H, illustrated in detail in Figs. 7 to 11, includes an upper block 134, a lower block 135, and a shell 136 connecting the two, a space 137 being formed between the upper and lower blocks within the shell. The shell itself may consist of several pieces, as is more clearly indicated in Fig. 10, each piece corresponding in shape to one side of the upper and lower blocks, and the several pieces united in a suitable manner, such as by bronze welding. The upper and lower blocks are provided with peripheral rims 138 to permit the shell 136 to be attached thereto in a suitable manner, such as by bronze welding, and at the same time obviate the possibility of overheating the shell due to a difference in thickness of section. The rim of the lower block also forms grooves which permit the cooling medium to be circulated around the lower block closer to the lower surface, which is directly exposed to heat.

The lower surface of the lower block 136 has a central portion, as in Fig. 8, consisting of a front lower surface 139 and rear surfaces or steps 140, 141, and 142, stepped upwardly from the front lower surface. Each of the central surfaces is adapted to be positioned substantially parallel to the top surface of the rail end, and the head H is also provided with two wing portions 143, one on either side of the central portion, the lower surfaces of which slant outwardly and downwardly.

As in Figs. 8 and 11, each of the steps 140, 141 and 142 may carry a lateral row of tips, in this instance six tips in each row, while the front lower surface 139 may carry three lateral rows

of tips, each row in this instance consisting of six tips. The tips in the lateral rows of the front lower surface and steps are preferably aligned longitudinally, to form six longitudinal rows, each longitudinal row being supplied with the combustible mixture from one of six headers 144, 145, or 146 disposed longitudinally and slanting upwardly from front to rear. The headers in this instance are drilled from the front face of the lower block, the ends thereof being closed by plugs 144', 145', and 146', respectively, which are secured in the ends of the headers in a suitable manner, such as by brazing or silver soldering. Each tip is connected with its respective header by an individual outlet passage 147. Each of the wing portions 143 may carry a longitudinal row of tips, in this instance three in number, each row of wing tips being supplied with the combustible mixture from a header 148, the end of which is closed by a plug 148'. Each wing tip is connected with its respective header by an individual outlet passage 149.

Since the lateral rows of tips carried by steps 140, 141, and 142 are spaced at increasing distances from the top surface of the rail end, a heating effect of decreasing intensity will be obtained which will tend to cause a decreasing hardness and also a decreasing depth of hardened zone in a direction away from the rail end.

30 The tips in the two central longitudinal rows preferably have outlets of a slightly larger diameter than the outlets of the tips in the outer rows in order to provide a greater heating effect at the center of the rail head where heat tends to be conducted away at a faster rate. In addition, the length of the various tips may be made shorter or longer in order to provide a desired heating effect. For instance, the three tips carried by the front lower surface and in each of the outer rows 35 may be shorter in the case of lighter rail, such as 112 lb. rail, than in the case of heavier rail, such as 130 lb. rail.

30 The wing tips are adapted to apply heat to the curved corners of the rail head, as can be seen 45 from Fig. 2, and also preferably have outlets of a larger diameter for a larger size of rail. The individual outlet passages 147 and 149 are threaded to receive the tips T, and in order to alter the tip arrangement, it is only necessary to replace 50 any tip by one of the desired length and size. Furthermore, in case it is not desired to harden the curved corners of the rail head, the wing tips may be replaced by suitable plugs, and in addition, any of the other tips may be replaced 55 by plugs in order to achieve a desired heating effect.

To convey the combustible mixture from the inlet 77 of the upper block to the tip headers in the lower block, the inlet 77 is connected by 60 cross passages 151 to the mid-portions of a pair of main headers 152 in the upper block, and a plurality of tubes 154, 155, 156 and 158 lead from the two main headers in the upper block to the tip headers in the lower block, these tubes 65 passing through the space 137. As in Fig. 7, the front and rear pairs of tubes 154 lead to the two middle tip headers 144, the next pairs of tubes 155 lead to tip headers 145, the pairs of tubes 156 lead to headers 146, and the single central tubes 158 lead to wing tip headers 148. By this arrangement, the pressure of the combustible mixture flowing to each of the tips tends to be equalized, since, while tubes 158 are longest, they connect with the main headers 152 at the central portions thereof at inlets 151 and thereby tend

to receive a slightly greater amount of the mixture, while the other tubes of diminishing length connect with the main headers at points further removed from the central portions. Thus, the greater resistance to flow of the combustible mixture of the longer tubes is compensated for by the tendency of the longer tubes to receive a greater amount of the mixture from headers 152.

In order to cool the head H adequately and in order to distribute the cooling medium evenly through the lower block, relatively large cooling medium headers 160 and 161 are formed in the lower block at either side of and slightly below the outer tip headers 146, and similarly slope upwardly from front to rear. The ends of headers 160 and 161 are closed by plugs 160' and 161', the plugs being secured in the ends of the headers in a suitable manner, such as by brazing. A series of channels and passages connect headers 160 and 161 and also distribute the cooling medium around and between tip outlets 147 and also through wings 143. These channels and passages are disposed between the tip headers and the lower surface of the block, and principally discharge into spaces 162 formed between the lower block and shell 136 and between the lower block and rim 138.

As in Fig. 10, headers 160 and 161 are connected by five channels, i. e. two front channels 163, a center channel 164, and two rear channels 165 and 166. The lower block is provided with a shoulder 167, as in Figs. 7 and 10, to facilitate drilling of these channels through the shoulder and header 160 and thence into the header 161. The ends of front channels 163, center channel 164, and rear channel 165 are closed by suitable plugs 163', 164', and 165', respectively, the plugs being secured in the ends of the channels in a suitable manner, such as by brazing. The rear channel 166 is not plugged, preferably being drilled entirely through the lower block. A series of passages 168 connecting the front channels 163 and disposed between alternate tip outlet passages 147 discharge the cooling medium into the space 162 at the front of the lower block, while a similar series of passages 169 connecting the rear channels 165 and 166 and also disposed between alternate tip outlet passages discharge into the space 162 at the rear of the lower block. In addition, a series of passages 170, as in Figs. 7 and 8, lead from the central channel 164 to the upper surface of the lower block, thus providing a positive circulation of cooling medium to the upper surface. Furthermore, the rear passages 169 are disposed in a plane above the plane of passages 168 in accordance with the steps in the lower surface, as in Fig. 8, and channels 164, 165, and 166 are successively higher with respect to front channels 163.

The circulation of the cooling medium through the wings 143 is similar to the circulation through the central part of the lower block, a series of passages and cross passages being employed. In each wing, two front passages 171, a central passage 172, and a rear passage 173 lead from header 160 or 161 to spaces 162 at the sides and at the rear of the wings. Each of these passages is substantially parallel to the lower surface of the respective wing, and front passages 171 and central passage 172 are disposed between wing tip headers 148 and the lower surface of the wing, front passages 171 passing between tip outlet passages 149, as in Fig. 9. Cross passages 174 connect front passages 171 and discharge into space 162 at the front of the wings.

The headers 160 and 161 receive the cooling fluid through tubes 175 from inlet passages 176 in the upper block 134, while the cooling fluid supply tubes 59, of Figs. 1-3, are attached to inlet connections 177, in turn attached to the upper block within inlet passages 176. The cooling medium, after circulation through the lower block, passes upwardly, completely filling chamber 137 and thereby cooling the combustible mixture tubes 154, 155, 156 and 158, and is discharged from the chamber 137 through an outlet passage 178 in the upper block. An outlet connection 179, secured to the upper block within the outlet passage 178, is connected with the tube M of Figs. 1-3, through which the cooling medium is passed to the jacket of the adaptor A, as previously described.

The quenching head Q, illustrated in detail in Figs. 12-14, comprises a single block attached to the supporting rods 50. The air hose 86 is connected to an inlet 181 which leads into a distributing chamber 182 from which the quenching air is conveyed through a plurality of channels 183 into an outlet header 184. The channels 183 may be drilled from the upper end of the block through outlet header 184 and into distributing chamber 182, the ends of the drilled holes being closed by suitable plugs 185, while the chamber 182 and header 184 may be drilled from the side of the block and the ends thereof respectively closed by an attached plug 186 or a removable plug 187. Leading from the header 184 are a plurality of outlets 188, which are disposed in three rows and are adapted to direct a plurality of air jets onto the heated surface at increasing distances away from the end of the rail, the upper row of outlets directing air jets onto points further back from the end of the rail than the two lower rows. The two middle channels 183 are so placed with respect to the inlet 181 that air will not pass directly into header 184 from the inlet, thereby effecting a more uniform distribution of air to the outlets.

The front face of the quenching head Q is obtuse in shape, the lower portion 189 of the face being adapted to contact the end of the rail when the head is in quenching position, as in Fig. 1, so that the quenching jets will be directed at an angle of substantially 20° with respect to the surface under treatment. In addition, the quenching head is of such width that it will fit between the wings of the heating head H when in quenching position. Obviously, the angle at which the quenching jets are directed may be varied, and the arrangement as well as the sizes of the quenching outlets may be changed as desired for any particular rail to be treated.

The protective air-screen head S, which is illustrated in detail in Figs. 15 and 16, comprises a hollow tube attached in fixed position to the lower horizontal tubes 23, as previously described, the ends of the tube being closed by plugs 190 secured therein in a suitable manner, such as by brazing. The hose 87 is connected to an inlet 191 attached to the tube, and the inlet is inclined slightly away from set screw 35 mounted in stop 33 to facilitate access to the set screw. Two sets of outlets 192, disposed at either side of stop 33, direct air jets at a slight angle upwardly and forwardly on either side of the rail and toward the web engaging rollers 30; while a row of outlets 193 direct air jets rearwardly and upwardly toward the quenching head in retracted position Q'. The outlets 192 may be inclined upwardly at an angle of 10° with the horizontal, while out-

lets 193 may be inclined rearwardly at an angle of 35° with the vertical, but other angular relationships, as well as other positions of outlets 192 and 193, may be employed.

In a complete set-up for the hardening of a plurality of rail ends when the rails are stored on docks or similar places, certain auxiliary apparatus is normally utilized. In a complete set-up, as illustrated in Fig. 17, the auxiliary apparatus includes the timing mechanism D; a pump 200 for circulating the cooling medium through the framework and through a coil 201 disposed in a cooling tank 202; an oxygen regulator 203 connected to an oxygen supply line 204; an acetylene regulator 205 and hydraulic back pressure valve 206 connected to an acetylene supply line 207; and an air regulator 208 connected to a compressed air supply line 209.

The oxygen supply line 204 is connected with a suitable source of oxygen, such as a plurality of cylinders of compressed oxygen connected to a manifold, and the outlet of the oxygen regulator 203 is connected with the oxygen inlet connection just beneath the cabinet C by a hose 210. The acetylene supply line 207 may be connected with a plurality of cylinders containing compressed acetylene connected to a common manifold, or to an acetylene generator. The hydraulic back pressure valve 206, which is provided with a relief valve 211, is connected with acetylene regulator 205 by a pipe 212, and the outlet of the acetylene regulator is connected with the acetylene inlet just beneath the cabinet C by a hose 213. Similarly, the outlet of the compressed air regulator 208 is connected with the air inlet just beneath the cabinet C by a hose 214. Additional valves may be placed in oxygen, acetylene, air supply, or connecting lines, as desired.

The cooling medium is circulated through a closed system which includes the framework F, the pump 200, and the cooling coil 201. A hose 217 connects outlet 218 of pump 200 with the cooling medium inlet I, while a hose 219 connects the cooling medium outlet O with cooling coil 201. A cooling fluid, such as water, may be circulated through tank 202 from an inlet 220 to an outlet 221. From the coil 201, the cooling medium passes into a relief tank 222 mounted above tank 202, which is subject to atmospheric pressure, the height of liquid in the relief tank being ascertained by a gauge 223. From the relief tank, the cooling medium flows by gravity through a hose 224 to inlet 225 of the pump 200, from whence it is recirculated through the closed system, the pump outlet being provided with a relief valve 226 and a by-pass connection 227 leading to the pump inlet, in order to prevent development of excessive pressures within the cooling system. A valve 228 is used for stopping the flow of cooling medium to the pump and through the closed system.

The pump is driven by a motor 230 to which it is directly connected. Disposed above the pump and motor is a panel 231, upon which is mounted the time delay relay D, which is connected with the heat-treating apparatus by the cable E. Also mounted on panel 231 is a control box 233 containing controls for the motor, such as a starting relay and switches, which are electrically connected with the motor by a cable 234.

While on the docks, the rails normally are stored horizontally on a plurality of spaced-apart and parallel rails or beams 235, supported at a convenient height by a column 236. The rails are normally placed parallel to one another,

with the ends aligned laterally and the base of each rail abutting the base of each adjacent rail; and, as previously pointed out, the embodiment of this invention as illustrated is particularly adapted to permit the treatment of a plurality of adjoining rail ends when the rails are stored in this manner. For such treatment, hoses 210, 213, 214, 217, and 219 and electrical cable E, all of which connect the auxiliary apparatus with the heat-treating apparatus, are preferably relatively long since the heat-treating apparatus is light and portable and can be moved easily from one rail end to another, whereas the auxiliary apparatus is more bulky and cumbersome and preferably remains relatively stationary. However, the auxiliary apparatus may be mounted upon a car, truck, or other movable support, and moved occasionally as necessity requires. Furthermore, since the treatment is effected at the mill or other places at which rails are stored, rather than on track itself, there is no necessity for removing a mobile unit from a track upon the approach of a train or handcar.

The ends of rails as they come from the mill are usually covered with a thin layer of scale which acts as insulation and tends to necessitate a relatively longer heating time. To remove this layer of scale, a welding torch may be passed several times over the area to be hardened so that the heat from the welding torch will cause the scale to expand and thereby become loosened, after which it will normally be blown away by the force of the ordinary welding flame.

In treating a rail or a plurality of rails by the apparatus described, after the various parts have been connected together, the relief tank 222 is filled with cooling medium and motor 230 is started to start pump 200. The carrier or framework is placed on a pilot rail for adjustment of the heating flames, since the full effect of the heating flames would tend to destroy parts of the apparatus even though a cooling medium were being circulated therethrough. The oxygen and acetylene are then turned on and the pressure thereof adjusted by regulators 203 and 205; the pilot tip P is lighted and the pilot flame adjusted; the lever L is held in the "on" position to cause a flow of oxygen and acetylene through the blowpipes to the heating head H; the proportions of the combustible mixture are adjusted by the blowpipe valves to produce the desired flames at the tips T; and the lever L is released, thereby shutting off the flow of combustible heating mixture. The heat-treating apparatus is then placed on a rail the end of which is to be treated.

The framework or carrier F is then aligned centrally with respect to the rail by adjustment of rollers 30; the lower surface of the head H is set parallel to the top of the rail end by adjustment of angles 26; the apparatus is adjusted endwise of the rail by set screw 35; and the distance between the tips T and the top of the rail is adjusted by clamps 21 and post 44, the cabinet C, blowpipes B, and head H all being moved as a unit. The apparatus will then be in the position of Figs. 1 and 17, and in position for the heat-treating operation itself.

After the apparatus is in position, the compressed air may be turned on and the pressure thereof adjusted by regulator 208; the time delay relay is adjusted to act at the end of the desired interval and electricity is supplied thereto; and flow of cooling fluid through tank 202 is started, if necessary. Then, merely by moving the lever

L to the "on" position, the heating gases will be turned on, the quenching head Q retracted, air will be passed to the protective screen head S, and the automatic timing mechanism started, as previously described. At the end of the predetermined time interval, the lever L will automatically be shifted to the "off" position, resulting in the heating gases being turned off, the quenching head thrown forwardly into quenching position, and the quenching air turned on. After the heated surface of the rail end has been cooled sufficiently, the apparatus may be moved to the next rail, the end of which is to be treated. During such removal, it is unnecessary to turn off the compressed air, inasmuch as it may be passed continuously through the quenching head during movement without inconvenience.

To remove the heat-treating apparatus from a rail end which has been treated and place the same upon an adjacent rail end which is to be treated, the front handle 39 is lifted so that angles 26 will be lowered from contact with the head or ball of the rail and so that rear skids 37 will support the rear end of the apparatus upon the top of the rail, the lower skids 25 being raised slightly above the upper surface of the base V of the rail. The apparatus is then slipped forwardly on the rail until rear skids 37 approach the end, in which position the rear handle 36 is used in lifting the apparatus entirely clear of the rail.

To place the apparatus upon an adjacent rail, the rear skids 37 are placed upon the top of the rail which is to be treated closely adjacent the end thereof, angles 26 being below the ball or head of the rail, and the apparatus slid onto the rail until flange 34 of stop 33 contacts the web, whereupon front handle 39 is lowered so that angles 26 will contact the ball and lower skids 25 will rest upon the base of the rail, set screw 35 at the same time acting to position the apparatus endwise of the rail. During this movement, eccentric rollers 30, having previously been set for the first rail of a plurality of similar rails, will center the apparatus with respect to the rail upon which the apparatus is being placed. Having again assumed the position of Figs. 1 and 17, the apparatus will be in position to heat treat the rail end on which it has just been placed, and the previously described operations are repeated.

From the above, it can be seen that it is necessary to adjust the apparatus for only the first of a plurality of similar rails to be treated, and that after proper adjustments for the initial rail, the only operations necessary are removal of the portable apparatus from one rail to another and throwing the lever L to the "on" position in the case of each rail, the remainder of the operations proceeding automatically.

Although this invention and the apparatus thereof have been described particularly with reference to the heat-treatment of rail ends, it will be obvious that the principles of this invention may be utilized in the treatment of other metal bodies and that various changes may be made which will come within the spirit and scope of this invention.

What is claimed is:

1. In apparatus for surface hardening a metal body maintained in relatively fixed position with respect to a support during treatment, the combination comprising means for locally heating a surface portion of said body; a movable quenching head for applying a cooling medium to the

heated surface; means for moving said quenching head into and out of operative position with respect to said surface; and means for controlling the flow of cooling medium to said quenching head, said controlling means being associated with said moving means in such a manner as to cause the cooling medium to flow to said quenching head and be directed onto the heated surface substantially simultaneously with the movement of said quenching head into operative position with respect to said surface.

2. Heat treating apparatus comprising means for locally heating a surface portion of a metal body; a movable quenching head for directing a cooling medium onto the heated surface; means for moving said quenching head into and out of operative relation with respect to said surface; and means for directing a protective screen of cooling medium toward said quenching head when in inoperative position with respect to said surface.

3. Apparatus for heat treating a portion adjacent the end of a rail or the like, such apparatus comprising, in combination, a device for applying heat to said portion; a carrier for said device; means secured to said carrier and cooperating with portions of said rail or the like to guide said carrier longitudinally of said rail from one end toward the other end thereof, to position said device relatively to the portion to be heat treated; and means for clamping said carrier to said rail or the like, to maintain said device in substantially fixed position relatively to the portion to be heat treated, said means including at least a part of said guiding means and said means cooperating with portions of said rail or the like, including the underside of the head of said rail.

4. Apparatus for heat treating rails or the like as defined in claim 3, including means for adjusting the position of said heat applying device with respect to said carrier.

5. Portable apparatus for heat treating a tread portion adjacent the end of a rail, such apparatus comprising, in combination, a device for applying high temperature heat to said portion; a carrier for said device; and means engaging the head of the rail and the base of the rail and operable to hold said carrier longitudinally on said rail and thereby maintain said device in fixed relation to the tread portion to be heat treated.

6. Apparatus for heat treating a tread portion adjacent the end of a rail, such apparatus comprising, in combination, a device for applying localized high temperature heat to said portion; a carrier for said device; and means secured to said carrier and constructed and arranged to cooperate with both the head and the base of said rail to guide said carrier longitudinally of said rail and abut the end of said rail to position said device relatively to said tread portion, said means being operable to hold said carrier on said rail to maintain said device in fixed relation to said tread portion.

7. Apparatus for heat treating rails and the like comprising means for locally heating a surface portion of the head of a rail; means for supporting said heating means; means attached to said supporting means for engaging the base of said rail on either side of the web thereof; means attached to said supporting means for engaging the underside of the head of said rail on either side thereof; and means attached to said supporting means for engaging the web of said rail on either side thereof.

8. Apparatus for heat treating rails or the like, comprising means for locally heating a surface portion of the head of a rail adjacent the end thereof; means for supporting said heating means above the head of said rail; a pair of skids attached to said supporting means for engaging the base of said rail adjacent the end and on either side of the web thereof; vertically adjustable means attached to said supporting means for engaging the head of said rail on either side thereof and at a point spaced from the end of said rail, whereby said adjustable means, during vertical adjustment thereof, will cause said supporting means to pivot about said skids; and means attached to said supporting means for contacting the end of said rail to position said supporting means and heating means longitudinally with respect to said rail.

9. Heat treating apparatus comprising means for locally heating a surface portion of a metal body; a movable quenching head for applying a cooling medium to the heated surface; means for moving said quenching head into and out of operative position with respect to said surface; means for directing a protective screen of cooling medium towards said quenching head when in operative position with respect to said surface; and means for controlling the flow of cooling medium to said quenching head and said protective means so as to effect a flow of cooling medium to said quenching head when said quenching head is in operative position with respect to said surface, and to effect a flow of said cooling medium to said protective means when said quenching head is in inoperative position with respect to said surface.

10. Heat treating apparatus comprising means for heating a surface portion of a metal body; means for controlling the operation of said heating means; a quenching head for applying a cooling medium to the heated surface; means for controlling the flow of cooling medium to said quenching head; means including a lever for simultaneously operating both of such controlling means in moving from one position to a second position; a latch for holding said lever in one of said positions; a solenoid operatively connected with said latch for causing said latch to be tripped; and an electrically operated timing mechanism associated with said solenoid for effecting operation of said solenoid at the end of a predetermined time interval so as to cause said latch to be tripped and said lever released, thereby operating both of said controlling means and causing the heating to be discontinued and substantially simultaneously therewith the cooling medium to be applied to such heated surface.

11. Heat treating apparatus as defined in claim 10, in which said solenoid and said lever are associated with said latch in such a manner that upon a cessation of the supply of electrical energy to said solenoid said latch will be tripped and said lever released.

12. Heat treating apparatus as defined in claim 10, in which said solenoid and said lever are associated with said latch in such a manner that upon a cessation of the supply of electrical energy to said solenoid said latch will be tripped and said lever released, and which includes an electrical switch associated with said solenoid for interrupting the supply of electrical energy to said solenoid to cause said latch to be tripped and said lever released.

13. Apparatus for heat treating rails and the like comprising means for locally heating a sur-

face portion of the head of a rail or the like; a carrier for supporting said heating means and composed at least in part of hollow members; means secured to said hollow members and cooperating with said rail or the like for positioning said heating means relatively to the surface portion being heat treated; and means for circulating a cooling fluid through at least the portion of said hollow members closely adjacent said positioning means.

14. Apparatus for heat treating in succession surface portions of a plurality of rails disposed side by side with the webs of such rails in substantially a vertical position and the base of each rail closely adjacent or touching the base of the rail on either side thereof, such apparatus comprising means for locally heating a surface portion of the head of a rail under treatment and adjacent the end thereof; and means for contacting at least the head and end of said rail under treatment to support said heating means above the head of said rail, a portion of said supporting means being constructed and arranged to extend alongside the web of said rail on either side thereof but sufficiently closely to the web of said rail to prevent contact with rails on either side of the rail under treatment.

15. Apparatus for heat treating a surface portion adjacent the end of a rail or the like, such apparatus comprising, in combination, means for directing a plurality of high temperature heating flames against a surface portion of the head of a rail adjacent one end thereof; a carrier for contacting at least the head and the end of said rail to support said heating means in operative position above the surface portion to be treated, said carrier being so constructed and arranged as to be capable of being placed in position on a plurality of rails in succession; and means secured to said carrier for contacting the top of the head of the rail and also for contacting the upper portion of the base of the rail under treatment on either side of the web thereof before said heating means can contact the upper surface of said rail, so as to prevent damage to said heating means when said apparatus is placed on a rail to be treated.

16. Heat treating apparatus comprising means for locally heating a surface portion of a metal body; a quenching head for directing a cooling medium against the heated surface; means for supporting said heating means and said quenching head in operative position with respect to said surface portion; means for directing a protective screen of cooling medium toward said quenching head and toward parts of said supporting means tending to become overheated; and control means constructed and arranged to initiate operation of said heating means and simultaneously therewith effect a flow of cooling medium to said protective means, and also to discontinue operation of said heating means and substantially simultaneously therewith effect the flow of said cooling medium to said quenching means.

17. Heat treating apparatus as defined in claim 16, including a timing mechanism associated with said control means so as to cause said control means to discontinue operation of said heating means and effect the flow of said cooling medium to said quenching means at the end of a predetermined time interval of heating.

18. Apparatus for heat treating a surface portion of the head of a rail comprising a blowpipe head provided with wings on either side thereof,

a row of tips for directing heating flames onto the side of said rail head being disposed in each wing, and a plurality of lateral rows of tips being disposed between said wings, the ends of at least the forward rows lying substantially in a plane and the ends of at least the rear rows being consecutively stepped at increasing distances from said plane, to direct heating flames against the

5 tread surface of the head of said rail; means for supporting said blowpipe head in operative relation with respect to said surface portion; and means for supplying said blowpipe head with a combustible mixture of gases.

ODIN V. CARLSON.
ARTHUR K. SEEMANN.
